[57] **CLAIM**

The ornamental design for a table frame, as shown and described.

DESCRIPTION

FIG. 1 is a perspective view of a table frame embodying my new design;

FIG. 2 is a top plan view thereof;

FIG. 3 is a front elevational view taken from the left-hand side of FIG. 2; and

FIG. 4 is a rear elevational view thereof.

The dotted lines indicating a table top in FIGS. 1 and 2 have been shown for illustrative purposes only.

FIG. 1

FIG. 2

FIG. 3

FIG. 4
